DESIGN FOR A FLUSH VALVE OR SIMILAR ARTICLE

Samuel Collito, Jr., Newark, N. J.

Application May 6, 1937, Serial No. 69,192

Term of patent 3½ years

To all whom it may concern:

Be it known that I, Samuel Collito, Jr., a citizen of the United States, residing at Newark, New Jersey, have invented a new, original, and ornamental Design for a Flush Valve or Similar Article, of which the following is a specification, reference being had to the accompanying drawing, forming a part thereof.

Fig. 1 is a side view of a flush valve showing my new design; and

Fig. 2 is a top plan view thereof.

I claim:

The ornamental design for a flush valve or similar article, as shown.
